[57] CLAIM

The ornamental design for a combined headband and
flashlight holder, as shown and described.

DESCRIPTION

FIG. 1 is a side elevational view of a combined headband
and flashlight holder showing my new design;
FIG. 2 is a side elevational view of the opposite side
thereof;

FIG. 3 is a rear elevational view thereof;

FIG. 4 is a front elevational view thereof;

FIG. 5 is a top plan view thereof;

FIG. 6 is a bottom plan view thereof; and

FIG. 7 is a reduced scale top perspective view thereof,
the broken line showing of a head is for illustrative
purposes only.
